(57) **CLAIM**

The ornamental design for a tapered bottle, as shown and described.

DESCRIPTION

FIG. 1 is a top perspective view of the tapered bottle according to the present invention.

FIG. 2 is a top plan view of the tapered bottle of FIG. 1.

FIG. 3 is a bottom plan view of the tapered bottle of FIG. 1

FIG. 4 is another top perspective view of the tapered bottle of FIG. 1; and,

FIG. 5 is a front elevation view of the tapered bottle of FIG. 1.

The evenly-dashed broken lines in the drawings illustrate the portions of the tapered bottle that form no part of the claim.
